J. A. RUFFIN

NOISELESS TYPEWRITER

Filed April 11, 1923

Inventor:

John A. Ruffin,

By Spear, Middleton, Donaldson & Hall

Atlys.

UNITED STATES PATENT OFFICE.

JOHN A. RUFFIN, OF MIDDLETOWN, CONNECTICUT; HORACE EDWARD RUFFIN AND ALLAN E. RUFFIN EXECUTORS OF SAID JOHN A. RUFFIN, DECEASED.

NOISELESS TYPEWRITER.

Application filed April 11, 1923. Serial No. 631,414.

One object of the invention is to provide a simple and efficient swinging type bar organization which will be practically noiseless and with which a metal surfaced platen 5 can be used. Another object is to provide such an organization as will be applicable to typewriters of well known makes, such as the Underwood, Remington, and others, without changing the fundamental plan of 10 such machines or the general plan of their type bar baskets, it being necessary only to substitute my improvement for the type bars in said machines.

Other objects will appear from the following description and the features of novelty will be pointed out in the appended claims.

In the accompanying drawings:—

Fig. 1 is a side view of a key lever organization like that of the Underwood machine, with my improvement incorporated therein.

Fig. 2 is a view of the main type bar.

Fig. 3 is a view of the supplemental lever or presser attachment.

Fig. 4 is an edge view of Fig. 3.

Figs. 5, 6 and 7 are views of the type.

Fig. 8 is a sectional view through the type and the main and supplemental type bars on the line 8—8 of Fig. 1.

Fig. 9 is a sectional view on line 9—9 of Fig. 1.

Figs. 10 and 11 are details, the latter figure showing one of the bent key levers off to the side of the keyboard.

In these drawings the finger key lever 1 is of ordinary construction, as is also the associated parts which are connected with the main type carrying member or bar 2. Instead of this bar carrying the type rigidly 40 fixed thereto, as in standard machines like the Underwood, etc., I mount the type slidably upon the upper end of this bar or lever, which, for this purpose, is provided with an opening 3 in which is slidably mounted a block 4. The type 5 is immediately mounted 45 on this block, being connected thereto by rivets, as shown.

This block 4 is made about one-thousandth of an inch thicker than the type bar 2, so that the type may slide freely in relation to the head of the lever or type bar 2, that is, without friction against the sides of the

said bar. There is a light spring interposed between the type and the bar 2, this spring being shown at 7. Its function is 55 to hold the type in normal position in relation to the type bar 2.

While I have shown one form of spring, it is obvious that this may be changed to other forms. A light spring may be used 60 here, offering little resistance to the forward movement of the type, in relation to the bar.

To the main type bar 2 there is pivoted 65 at 8, a supplemental lever 9. This supplemental lever is of flat metal having an offset head portion 10 with a laterally extending flange 11 along its front edge which extends across in rear of the head or upper portion of the main lever or bar 2, so as to press, when operated upon the rear end 70 of the type for making the printing impression. This supplemental lever is pivoted close to the head or free end of the bar or lever 2, making a short lever arm here, and its long arm 9a extends along the 75 bar 2 towards the pivot of the latter. It is provided at its end with an ear 12 extending across the edge of the bar 2, and having riveted thereto a pin which at its other end extends through an ear 13 formed 80 on the rear edge of the bar 2 and extending laterally in respect thereto.

A spring 14 encircles the pin and bears at its ends against the ears 12 and 13.

There is a space at 18 between the front 85 edge of the head of the bar 2 and the rear face of the type, allowing play at this point so that the bar 2 at its upper front edge will not strike the type and impinge it upon the platen with a blow, and there is also play at 90 19, for the same reason, between the rear wall of the opening 3 and the rear face of the block 4.

When the key is depressed, the main type bar 2 is swung up from its substantially 95 horizontal position towards the platen and when it reaches the position shown in dotted lines in Fig. 1 the ear 12 of the supplemental presser lever 9 will strike against the noiseless stop 15 mounted on the frame, and the general forward movement of this lever 100 9, will be arrested at this end. The main bar will continue its forward movement slightly but, owing to the play between the

slidable type and said lever 2, the type will not be thrown forcibly against the platen thereby, but there will occur a relative movement between the main and supplemental levers, resulting in a pressing action of the type against the platen instead of a blow. In other words, the forward movement of the bar 2 will be partly checked when the supplemental type bar 9 strikes the noiseless stop, and it will have some further though retarded movement against the yielding resistance of the spring cushion 14, sufficient to get the relative pivotal movement of the supplemental type bar 9 for moving the type against the platen by the pressing action before referred to, thus eliminating the noise which results from a blow of the type upon the platen.

Further, by reason of the fact that the pivot 8 of the supplemental lever is near to its outer end, the leverage will be such that the pressure exerted will be multiplied and rendered sufficient for maximum manifolding.

25 The stop 15 receives the shock of the blow, as the composite type bar is operated forward. This stop being of rubber or other non-sounding material, it is obvious that there is no noise in taking the blow of the composite type bar. The forward printing action of the type is accomplished by the supplemental or presser lever 9 swinging around its pivot, pressing the type in a horizontal line to the printing point.

30 A stop pin 16 on the lever 2 enters a slot 17 in the supplemental lever 9 and limits the separating movement of these levers relative to each other.

35 The stop 15 may be either of rubber or of other noiseless material, such as leather.

I do not limit myself to the mechanism described, as this may be changed without departing from the underlying principles of the invention. The drawings and specification are presented as illustrative of one form in which the invention may be embodied, and not as being restrictive upon the scope of the invention, which is defined by the appended claims. Thus I do not limit myself to mounting the type slidably on the bar 2, as the type may be otherwise related to the supplemental lever 9 to be pressed thereby against the platen.

40 It will be observed that standard makes of typewriting machines now being made can be rendered noiseless by using my improved composite type bar instead of the ordinary type bar, and standard machines can be converted into noiseless ones by taking out the standard bars and substituting therefor the composite type bars described above.

45 A metal surface platen can be used with my invention, thereby producing clearer cut manifold copies than ones made on rubber covered platens.

The spring 7 restrains the movement of the type member and as the head of the lever 10 bears on this type member it is obvious that the movement of the upper end of this lever is restrained also.

70 I claim:

1. A composite swinging type bar for typewriting machines comprising a main bar pivotally mounted and operated by a key lever, a supplemental bar pivoted to the main bar, and having movement relative thereto, a type member slidable on the main bar and pressed against the platen by the supplemental bar, and a noiseless stop against which the supplemental lever strikes on the forward movement of the type bar, substantially as described.

75 2. In combination a swinging type bar for typewriting machines, a type member carried by said bar and movable relative thereto, means for retarding the movement of the type member towards the platen, means carried by the swinging type bar independently of said type member for moving the type member in relation to the swinging type bar and pressing it against the platen and stop means for arresting the movement of the swinging type bar and for operating the said means to perform its pressing action on the type member, substantially as described.

80 3. In combination in type bar actions for typewriting machines, a swinging bar, a key lever for swinging said bar towards the platen, a supplemental bar or lever pivoted to the bar first mentioned and movable therewith, a noiseless stop fixed to the frame of the machine and against which the supplemental lever strikes, type pressed by the supplemental bar upon the platen, and a spring between the main and supplemental bars which yields in checking the forward movement of the swinging bar and allows the supplemental bar to move in relation to the main bar to press the type upon the platen, substantially as described.

85 4. In a typewriting machine, a type bar, a platen a type slidable on the type bar for printing by pressure in combination with means mounted on the type bar for exerting said pressure, and a stop on the frame for operating said means when the type bar is moved to a position adjacent the platen.

90 5. In combination, in a typewriting machine, a key lever, a bar pivotally mounted and operated towards the platen by said key lever, a type member, a lever pivoted to the bar near the free end thereof, and having its longer arm between said pivot and the pivot of the bar, a stop on the frame against which said longer arm impinges, a spring between the bar and the lever carried thereby to check the forward movement of the bar, but to allow said bar to have further movement after being checked to thereby

secure a relative movement of the lever about its pivot on the bar, said lever in said relative movement pressing the type member upon the platen, substantially as described.

- 5 6. In combination, in a typewriting machine, a key lever, a bar pivotally mounted and operated towards the platen by said key lever, a type member, a lever pivoted to the bar near the free end thereof, and 10 having its longer arm between said pivot and the pivot of the bar, a stop on the frame against which said longer arm impinges, a spring between the bar and the lever carried thereby to check the forward 15 movement of the bar, but to allow said bar to have further movement after being checked to thereby secure a relative movement of the lever about its pivot on the bar, said lever in said relative movement pressing the 20 type member upon the platen, and a spring

for restraining free movement of the said lever and type member, substantially as described.

7. In combination in type bar action for typewriting machines, a swinging type bar, 25 a key lever for swinging said bar towards the platen, a supplemental bar or lever pivoted to the bar first mentioned and movable therewith, a yielding noiseless stop against which the supplemental lever strikes for 30 swinging the supplemental bar or lever in relation to the main bar, type movably mounted in the type bar independently of said supplemental bar to be pressed by the supplemental bar upon the platen, and means 35 for restraining the free movement of the supplemental bar, substantially as described.

In testimony whereof, I affix my signature.

JOHN A. RUFFIN.
